UNITED STATES PATENT OFFICE.

JAMES H. CARMEAN, HAROLD F. ROBERTS, AND JOHN M. ROBERTS, OF KANSAS CITY, MISSOURI.

MANIFOLD-STOVE.

1,400,023.

Specification of Letters Patent. Patented Dec. 13, 1921.

Application filed December 26, 1919. Serial No. 347,472.

To all whom it may concern:

Be it known that we, JAMES H. CARMEAN, HAROLD F. ROBERTS, and JOHN M. ROBERTS, citizens of the United States, residing at 5 Kansas City, in the county of Jackson and State of Missouri, have invented certain new and useful Improvements in Manifold-Stoves; and we do declare the following to be a full, clear, and exact description of 10 the invention, such as will enable others skilled in the art to which it appertains to make and use the same, reference being had to the accompanying drawings, and to the letters and figures of reference marked 15 thereon, which form a part of this specification.

This invention relates to a hot plate or stove adapted to be heated by the products of combustion of an explosion engine, means 20 being provided whereby the exhaust gases may pass through the heater or stove preparatory to exhausting into atmosphere.

Means is also provided whereby the heat energy will be absorbed within the heater 25 and communicated to a part from which it may be transmitted to cooking utensils.

It is well known that considerable heat energy from the ignited charge in the combustion chamber of an explosion engine is 30 dissipated through the exhaust manifold or muffler. Our invention contemplates the provision of means whereby this otherwise wasted energy may be utilized for the purpose of cooking, whether the engine is stationary or movable. For example, the device contemplated by our invention is adapted to be attached to the engine block in lieu of the exhaust manifold and to collect or absorb some of the heat of the gases 35 passing from the engine cylinders and render it available for cooking purposes.

We have shown our invention as applied to an engine of a motor vehicle so that the heater or stove is rendered portable, permitting the food of a tourist to be cooked 45 during transit, the device being so constructed that it may be mounted within the hood without affecting any of the standard parts except that it is designed to take the place of the usual exhaust manifold common 50 to engines of motor vehicles.

In the drawings,

Figure I is a side elevational view of a device constructed in accordance with our 55 invention.

Fig. II is a perspective view of a heater or stove constructed in accordance with our invention, parts being broken away to illustrate the interior heat absorbing fins.

Fig. III is a cross sectional view through 60 the heater.

Fig. IV is a view of the heater, showing an even attached thereto.

The heater is illustrated as consisting of a substantially rectangular box or housing, 1 having inlet ports 2, 3, 4 and 5 adapted to be connected to the engine block for the respective cylinders in place of the exhaust manifold, it being assumed that the device illustrated is for a four cylinder engine. 70 The hollow casing or housing 1 provides a heat chamber 6 in which are arranged a plurality of longitudinally disposed heat-absorbing fins or walls 7, welded or otherwise secured to the top plate 8 of the housing so that the bottom edges of the fins may be disposed above the floor 9 thereof, leaving a space through which the products of combustion may pass in such a manner that the heat therein will be absorbed by the fins 75 and conducted to the top plate 8, or at least, the major portion of the heat will be available at the top plate in a manner common to stoves and other heating devices.

The fins 7 may be of varying cross sectional areas, preferably with the center fin of greatest area to maintain the longitudinal center of the plate 8 at the highest temperature, as will be readily understood. The products of combustion, that is, the exhaust 90 gases, may pass out through the exhaust pipe 10 through the muffler at the end of the housing 1 in the usual manner.

On the side walls of the housing we prefer to arrange studs or projections 11 to cooperate with a row of projections 12 to hold utensils on the heater or stove; for example, the utensils 13 and 14 may be provided with studs or projections 15 and 16 to be engaged by the hooked ends 17 and 18 of the springs 100 19 and 20, having hooked ends 21 and 22 respectively to engage the studs or projections 11 and 12, dependent upon the side of the receptacle on which the springs are located.

When the parts are assembled as shown in Fig. I, and the engine is operating to propel the motor vehicle, the products of combustion will pass through the housing 1, heating the chamber 6, and the fins 7 will 110

conduct the heat to the top of the housing in a well understood manner, it being apparent that the cooking utensils may be yieldingly held upon the plate 8 by the springs just 5 described so that while the vehicle is traveling over the road bed, the utensils will not be lost or become detached from the plate 8, which is illustrated as being in the form of a hollow shelf.

10 While the major portion of the heat will be conducted to the top of the housing, it is also apparent that considerable heat will be radiated from the bottom plate of the housing and if desired, an oven 23 may be suspended from the housing by the links or slings 24 and 25 so that the heat generated in the stove may raise the temperature of the oven to a sufficient degree to permit baking.

15 What we claim and desire to secure by Letters Patent is:

20 1. A heater attachment for the exhaust of explosion engines consisting of a hollow casing having a tubular inlet to receive the products of combustion of the gas engine 25 and an outlet, a central, longitudinal, heat conducting fin depending from the top of

the hollow casing, and additional fins spaced from and on opposite sides of the central fin, the second mentioned fins being of less area than the central fin so that the major 30 portion of the heat will be conducted to the central portion of the top of the casing.

2. A heater for attachment to the exhaust of explosion engines consisting of a hollow casing having a tubular inlet to receive the 35 products of combustion of the gas engine, said casing having an outlet port, heat conducting fins carried by the top of the casing and within the same, the heat conducting fins having varying areas progressively decreasing from opposite sides of the longitudinal center, outstanding pins carried by the side walls of the casing, and yielding utensil-engaging members coöperating with the pins to hold the utensils onto the top of 40 the casing.

45 In testimony whereof we affix our signatures.

JAMES H. CARMEAN.
HAROLD F. ROBERTS.
JOHN M. ROBERTS.
